UNITED STATES PATENT OFFICE.

FRANCIS W. GIBSON, OF WEST ROXBURY, AND CLARENCE S. MARDEN, OF CAMBRIDGE, MASSACHUSETTS, ASSIGNEES TO THE H. D. BEACH COMPANY, A CORPORATION OF NEW JERSEY.

BOX DISPLAY-COVER.

1,115,422.

Specification of Letters Patent. Patented Oct. 27, 1914.

Application filed April 21, 1913. Serial No. 762,490.

To all whom it may concern:

Be it known that we, FRANCIS W. GIBSON and CLARENCE S. MARDEN, citizens of the United States, residing, respectively, at West 5 Roxbury, county of Suffolk, State of Massachusetts, and Cambridge, county of Middlesex, State of Massachusetts, have invented certain new and useful Improvements in Box Display-Covers, of which the following is a specification.

This invention relates to display boxes for goods and particularly to a display box cover which will permit the effective display of advertising matter indicative of the 15 nature of the goods and which will at the same time protect the goods against damage or deterioration. The retail cigar trade offers a field in which the need of such a device has been long felt, and in the further 20 discussion of our invention we will describe and illustrate our display cover as particularly designed for this purpose, although it is of course understood that the rack is capable of use in any other capacity where 25 it would serve the purposes intended. In the display of cigars it is essential that they shall be protected against the drying effect of the air and against contamination by dust, germs and similar deleterious matter. But 30 it is equally as essential that the cigars shall be readily accessible when making a sale and that their oftentimes artistic labels and bands shall be exposed in plain view to indicate the particular brand. In fact, this 35 latter requirement is now law, and therefore the need of an adequate display rack is all the more imperative. This combination of attractive label and band moreover, presents a pleasing appearance to the eye and its 40 value as a selling medium is well recognized by dealers. The usual method of display employed at the present time is to place the open boxes of cigars inside and on the tops of show cases with their covers thrown 45 back to expose the banded cigars and at the same time to display the label on the inner face of the box cover at the most effective reading angle. This method, where the cigars are displayed on top of the show 50 cases, is an extremely unsanitary one and is open to the further objection that the cigars

are exposed to the drying effect of the air and soon depreciate in quality.

To the end therefore of producing a display box and cover which will overcome 55 these objections and which will be capable of production at a low figure, we have devised our present invention in which we fit a transparent cover over the hinged cover of a cigar box in position to rest on the box 60 edges and protect the cigars and at the same time to display the label on the inner face of said cover. The transparent cover is so disposed with respect to the hinged cover as to hold the hinged cover erect while utilizing 65 the cover hinge in its own lifting movement.

The construction and use of our display box cover will be more fully discussed in the specification which follows, and in the drawings which form a part of that specification we have shown an illustrated embodiment which has been found well adapted for the purposes intended and the requirements of the trade.

Throughout specification and drawings 75 like reference numerals are employed to indicate corresponding parts and in these drawings: Figure 1 is a plan view of a display box and cover in accordance with our invention, Fig. 2 is a transverse section on 80 the line 2—2 of Fig. 1, Fig. 3 is a partial bottom view of the open frame which fits over the box cover and carries a transparent plate to protect the contents of the box, Fig. 4 is a detail of one of the locking strips 85 for the transparent plate. Figs. 5, 6 and 7 are end, plan and front views, respectively of a slightly modified construction, and Figs. 8 and 9 are detail sections on the lines 8—8 and 9—9, respectively of Fig. 6. 90

The display box and cover thus illustrated comprises a container 1 having a hinged cover 2. This container, as herein shown and discussed is the ordinary cigar box, and in use the cover is thrown back to expose 95 the contents and to display the label on its inner face.

To protect the cigars against depreciation and at the same time to expose their bands and the label on the box cover, we fit a covering 100 frame 3 over the box cover in position to lie across the delivery opening of the box. This

frame is preferably made of sheet metal in the shape and proportions of the cigar box, to rest flat on the walls thereof and project slightly over the edges to provide grasping portions for the hand in raising it when making a sale. The frame is, therefore, of open rectangular shape and provides a display opening 4 preferably co-extensive with the box to permit the cigars to be seen 19 without raising the frame.

To exclude air and germs from the cigars the display opening is covered by a transparent plate 5 held to the frame by three locking strips 6. These locking strips are 15 of the shape shown in Fig. 4 and are detachably held at their outer ends to the frame by the clamping flanges 7 thereof, which flanges are turned in along all four margins of the frame and pressed down upon the locking 20 strips on three sides. These flanges 7 thus provide rolled edges which will not cut the fingers when raising the cover. The plate 5, is therefore detachably held to the frame 3 on three sides thereof, preferably the front 25 edge and both ends, there being no locking strip for the upper or rear edge of the plate.

In lieu of a locking strip for the rear edge of the plate we provide locking lips 30 8 adapted to engage over said edge near each end. These lips are formed as projecting tongues and are turned in from the metal of the rear edge of said frame and then bent down over the rear edge of the transparent plate. Said lips have for their 35 function to prevent displacement of the plate, except when it is desired to withdraw it, in which event it is removed by first turning back the lips out of its path of travel and then displacing it by a sliding movement 40 transversely of the box. The plate in this movement is guided by the inner or free ends of the locking strips. These ends are formed as edge receiving clamps by turning the metal thereof upwardly at 9 in a plane 45 at right angles to the body portion thereof and inwardly at 10 in a plane at right angles to the portion 9 parallel to but in a higher plane than said body portion. The sockets thus provided form guides in which the 50 plate is slid by a transverse movement until its rear edge passes the locking lips, whereupon said lips are turned down to clamp the plate in position.

The plate and frame are fitted upon the 55 cover of the cigar box by a slot 11 formed in the rear wall thereof. This slot is formed by striking up the metal from opposite edges to provide a central flange 12 along the rear edge and side flanges 13 along the front edge. Against this flange 12 the upper face 60 of the box cover finds bearing, the lower face of said cover bearing against the flanges 13. Said flanges thus constitute 65 bearings and supports for the box cover, and have for their function the holding of

the cover in a position slightly inclined from the vertical to most effectively display the label borne upon the inner face thereof. The slot and flanges permit the transparent cover to utilize the hinges of the box cover 70 in its own lifting movement, thereby avoiding the use of a second set of hinges.

The method of assembling our improved display device is as follows: The frame 3 is struck out from the blank in a shape suitable 75 for the cigar box to which it is to be adapted. The display opening 4 and the longitudinal slot 11 having been struck out therefrom, the flanges 12 and 13 are turned up. The locking strips 6, which have already been 80 shaped in the fashion described, are next laid upon the frame near the bottom and end walls thereof, and the marginal flanges 7 are then turned down to clamp the outer edges of said strips. This clamps the locking strips to the frame. The transparent plate 5 is next inserted into the guides provided by the free ends of said strips by a movement transversely of the box. The locking lips 8 are now turned in and pressed 85 down upon the rear edge of said plate to hold it in position to cover the display opening. The frame thus assembled is then placed in covering position by inserting the slot 11 over the box cover which has been 90 thrown back and sliding said frame therealong until it abuts against the rear wall of the cigar box. In this position the upper side of the box cover finds bearing against the central flange 12 and the lower side 95 against the end flanges 13. This maintains the cover in a substantially vertical position and insures the proper display of the label 100 thereof. At the same time the frame 3 is resting upon the walls of the box with its 105 transparent plate covering the display opening. This insures proper display of the 110 cigars without subjecting them to outside exposure, the frame being lifted and by reason of its bearing upon the box cover swinging said cover backwardly and downwardly, when it is desired to remove a cigar.

In Figs. 5 to 9 inclusive, we have shown a slightly modified construction of frame. In this embodiment the frame is slit angularly 115 at two corners and bent downwardly to form front and end flanges 14 which provide advertising spaces of greater area than in the preferred embodiment. The frame near its rear edge has a longitudinal slot 15 similar to the slot 11 except that instead of three bearing flanges, we have provided one bearing flange 16 substantially co-extensive with the slot. Against this flange the box cover finds bearing. Additional bearings may be 120 provided for the cover by turning up a tongue 17 from the rear edge of the frame near each end of the slot as shown in Fig. 6. This construction of frame just described calls for a slightly different arrangement of 125 130

locking strip 19, for the transparent plate 20. Instead of turning back the margins of the frame to provide clamping flanges adapted to be pressed down on the strips, as in 5 the preferred embodiment, said margins are turned downwardly and inwardly, as shown in Fig. 9 and then downwardly and outwardly to provide the advertising areas 14. Into the recess thus formed by said downward 10 and inward turns the main portion of the locking strip is inserted, the free end thereof being bent as shown to receive and clamp the glass plate. The rear edge of the frame has no locking strip, the metal at each 15 end of the slot being turned downwardly and inwardly to provide locking lips 18 (see Fig. 8) which receive and clamp the glass. The upper face of the frame may bear any suitable advertisement, as for example the 20 brand and price of the cigars on display, while the plate, being transparent, permits the cigars to be seen without exposing them to the air. The frame is made detachable so that it may be removed from the box when 25 the contents thereof have been sold and transferred to a fresh box.

Various other modifications in the con-

struction and form of our invention may obviously be made if within the limits of the appended claims.

30

What we therefore, claim and desire to secure by Letters Patent is:

1. A display cover for a container having a hinged lid said display cover comprising a frame having a transparently covered display opening and a slot formed in its rear edge to receive said hinged lid and bearing flanges struck up from the edges of said slot to support said container lid in substantially erect position. 40

2. A display cover for a container having a hinged lid, said display cover comprising a frame having a transparently covered display opening and a slot formed near one edge to receive said hinged lid, and a bearing formed adjacent the slot to support said hinged lid in substantially erect position. 45

In testimony whereof we affix our signatures in presence of two witnesses.

FRANCIS W. GIBSON.

CLARENCE S. MARDEN.
